UNITED STATES PATENT OFFICE.

HERMAN C. PRIEBE, OF BLUE ISLAND, ILLINOIS.

DRAFT GEAR.

Application filed March 16, 1922. Serial No 544,182.

To all whom it may concern:

Be it known that I, HERMAN C. PRIEBE, citizen of the United States, residing at Blue Island, in the county of Cook and State of Illinois, have invented a certain new and useful Improvement in Draft Gears, of which the following is a full, clear, concise, and exact description.

My invention relates to draft gears employing mechanism for resisting draft strains. One feature of the invention relates to those draft gears which include inner and outer followers and rockers upon such followers having opposed faces and operating in conjunction with springs in opposing draft strains. Such a draft gear is shown in my Patent 1,282,940, dated October 29, 1918.

In accordance with one feature of my invention the rockers are hinged upon the followers to which they are respectively individual and where there are two sets of such rockers with one rocker of each set individual to each follower, the two rockers associated with each follower, in addition to being hinged upon such follower, are also hinged together, there being preferably a single pintle upon each follower upon which the rockers pertaining to such follower are hinged upon the follower and to each other.

In accordance with another feature of my invention the coupler yoke of a draft gear is caused directly to engage the inner abutment provided for the draft gear instead of having such engagement occur between the inner follower of the gear and such abutment.

I will explain my invention more fully by reference to the accompanying drawings in which Fig. 1 is a plan view, partially in section, illustrating the preferred form of draft gear with contiguous portions of the underframe car structure also illustrated; Fig. 2 is a sectional view on line 2—2 of Fig. 1; Fig. 3 is a sectional view on line 3—3 of Fig. 1; Fig. 4 is a sectional view on line 4—4 of Fig. 3; Fig. 5 is a sectional view on line 5—5 of Fig. 3; Fig. 6 is a perspective view illustrating the inner and outer followers of the draft gear; Fig. 7 is a perspective view illustrating the two sets of rockers, the two rockers shown upon the left of this figure pertaining to different sets and being hinged upon one follower, these particular followers being

shown in separated relation for the sake of illustration while the rockers shown at the right hand of this figure are complementary to the followers shown at the left of the figure and are illustrated in hinged connection; and Fig. 8 is a perspective view of one of the two links which are preferably employed in forming the coupler yoke.

Like parts are indicated by similar characters of reference throughout the different figures.

The coupler 1 has a coupler shank 2 with which the outer ends of the coupler yoke are assembled by means of a key 3 passing through a slot in the coupler stem and through the sides 4 of the yoke, these yoke sides being preferably in the form of individual links as illustrated in Fig. 8. The outer follower 5 is engaged by the coupler butt 6 and is moved inwardly when the coupler is subject to sufficient pushing strain. An inner follower 7 is engaged by the inner ends of the coupler yoke links 4 and is movable outwardly when the coupler is subject to sufficient pulling strain. A key 5' passes through the outer follower 5 and is engageable with the outer stops 8 to limit the outward movement of the outer follower. A key 7' passes through the inner follower 7. The draft gear is interposed between the center sills or draft sills 9, the keys 3, 5, and 7' passing through suitable slots formed in these sills. Forward or outward pull upon the inner follower is desirably not effected by the direct engagement of the coupler links 4 with the key 7' but is desirably effected by the engagement of the rear ends of these links with the lateral enlargements or formations 10 that are provided upon the inner follower 7. The slot 11 in the inner follower that receives the key 7' is desirably formed, in part, through said formations 10. The inner follower desirably also has an inwardly extending projection 12, upon its inner side, that is also interposed between and is engageable by the links to maintain them spaced apart at their inner ends. The links extend inwardly beyond the projection 12 so as to be directly engageable with inwardly projecting abutment portions of the cheek plates. The outer follower 5 may have formations 14 upon its sides for reception between the sides of the coupler links 4 to co-operate with the key 3 in positioning said links. The key slot 15 that re-

ceives the key 3 is desirably formed through the formations 14.

Springs 16 are interposed between the outer ends of the keys 5', 7', in accordance with common practice, being employed for the purpose of resisting coupler strains. Other springs 17, 18 are co-axial with the gear, being between the center sills 9 and being employed for a similar purpose. These springs 17 and 18 are respectively individual to the outer follower 5 and inner follower 7, there being two sets of such springs for each follower. The follower 5 is provided with inwardly extending projections 19 that enter the bores of the springs 17 while the follower 7 is provided with outwardly extending projections 20 that enter the bores of the springs 18. The formations 14 of the outer follower are extended inwardly sufficiently to form pintle sockets 21, Fig. 3. The formations 10 of the inner follower are extended outwardly sufficiently to form pintle sockets 22. Pintles 23 and 24 are respectively mounted in their supports 14 and 10.

There are two sets of rockers, the rockers 25 and 26 of one set being respectively individual to the followers 5 and 7 and the rockers 27 and 28 of the other set being, likewise, respectively individual to the followers 5 and 7. The rockers 25 and 27 of each set are hinged upon the pintle 23. The rockers 26 and 28 of each set and respectively complementary to the rockers 25 and 27 are hinged upon the pintle 24. The rockers 25 and 27 are formed with outwardly extending projections 29 that enter the bores of the springs 17. The rockers 26 and 28 are formed with inwardly extending projections 30 that enter the bores of the springs 18. These rockers operate, as is made clear by the aforesaid patent, in conjunction with springs in resisting draft strains and, by being hinged as described, are definitely placed and held in operating positions. The hinging reduces the tendency to breakage and aids in holding broken parts in place in the event of breakage. While the rockers of each set directly engage each other they are not to be thus limited, nor do I wish to be limited to the attachment of the formations or blocks 10 and 14 to the followers that are shown as carrying them, it being new with me to have these formations or blocks so assembled with the links of the yoke as to be guided thereby whether these formations or blocks are integral with the followers or not.

While I have herein shown and particularly described the preferred embodiment of the invention I do not wish to be limited to the precise details of construction shown as changes may readily be made without departing from the spirit of my invention, but having thus described my invention I claim

as new and desire to secure by Letters Patent the following:—

1. A draft gear including a coupler; inner and outer followers actuated thereby and movable each toward the other; springs, one individual to each follower, for resisting the approach of the followers toward each other; and two sets of rockers each set comprising two rockers having opposed faces, one rocker being individual to each follower and actuatable thereby, said rockers being interposed between and engaged by said springs to maintain the rockers in action and resist follower effected movement thereof, the two rockers that are individual to each follower being in hinged connection with each other and with the follower. 75

2. A draft gear including a coupler; inner and outer followers actuated thereby and movable each toward the other; springs, one individual to each follower, for resisting the approach of the followers toward each other; and two sets of rockers each set comprising two rockers having opposed faces, one rocker being individual to each follower and actuatable thereby, said rockers being interposed between and engaged by said springs to maintain the rockers in action and resist follower effected movement thereof, the two rockers that are individual to each follower being in hinged connection with each other. 30

3. A draft gear including a coupler stem; a yoke comprising two longitudinal links assembled at their outer ends with said stem; and motion resisting mechanism including a follower between said links and having formations on the sides thereof that are adjacent said links, said formations entering the links respectively adjacent thereto to couple said follower and links, said follower having an inwardly extending projection, upon its inner side, that is also interposed between and is engageable by said links. 100

4. A draft gear including a coupler stem; a yoke comprising two longitudinal links assembled at their outer ends with said stem; and motion resisting mechanism including a follower between said links and having formations on the sides thereof that are adjacent said links, said formations entering the links respectively adjacent thereto to couple said follower and links, said follower having an inwardly extending projection, upon its inner side, that is also interposed between and is engageable by said links; in combination with draft sills between which the draft gear is placed; a key passing through registering slots that are formed in said sills and through said follower and said link engaging formations on the follower; and abutments carried upon said sills and engageable by the inner ends of said links. 115

5. A draft gear including a coupler stem; a yoke; motion resisting mechanism includ- 130

ing a follower between the sides of said yoke; two rockers operated upon by said follower and also disposed between the sides of said yoke and in hinged assembly with 5 each other; and blocks having said rockers therebetween and with which the rockers are assembled to turn with respect thereto, said blocks and yoke being interengaged to guide the blocks in their movement longitudinally 10 of the gear.

6. A draft gear including a coupler stem; a yoke in the form of two links; motion resisting mechanism including a follower between said links; two rockers between said 15 links and operated upon by said follower and in hinged assembly with each other; and blocks having said rockers therebetween and with which the rockers are assembled to turn with respect thereto, said blocks being 20 respectively surrounded by said links and in engagement therewith to be guided thereby longitudinally of the gear.

7. A draft gear including a coupler stem; a yoke; motion resisting mechanism includ- 25 ing a follower between the sides of said

yoke; two rockers operated upon by said follower and also disposed between the sides of said yoke; a pintle upon which said rockers are hinged and extending across the space between the sides of the yoke; and 30 blocks, one upon each end of the pintle, that have engagement with and along the sides of the yoke to be guided in their movement longitudinally of the gear.

8. A draft gear including a coupler stem; 35 a yoke in the form of two links; motion resisting mechanism including a follower between said links; two rockers between said links and operated upon by said follower; a pintle upon which said rockers are hinged 40 and extending across the space between the sides of the yoke; and blocks, one upon each end of the pintle, respectively surrounded by said links and in engagement therewith to be guided thereby longitudinally of the gear. 45

In witness whereof, I hereunto subscribe my name this 27th day of January, A. D. 1922.

HERMAN C. PRIEBE.
